UNITED STATES PATENT OFFICE.

CARL WALKER KENDALL, OF EDGEWATER HEIGHTS, NEW JERSEY, ASSIGNOR TO
COLUMBIA MACHINE & STOPPER CO. INC., OF NEW YORK, N. Y., A CORPORA-
TION OF NEW YORK.

BOTTLE-CAPPING MACHINE.

1,299,355.

Specification of Letters Patent. Patented Apr. 1, 1919.

Application filed January 18, 1918. Serial No. 212,516.

To all whom it may concern:

Be it known that I, CARL WALKER KENDALL, a citizen of the United States, residing at Edgewater Heights, county of Bergen, and State of New Jersey, have invented certain new and useful Improvements in Bottle-Capping Machines, of which the following is a specification, reference being had therein to the accompanying drawings, 10 forming part thereof.

This invention is a bottle capping machine of the class used in applying that character of bottle closure generally known as the crown seal. The objects of the invention 15 are speed and reliability and efficiency in operation, adjustability to bottles of different lengths, accessibility of its working parts, and comparative cheapness, simplicity, compactness and lightness of structure. 20 Although the accompanying drawings illustrate only one embodiment of the invention, its broad inventive ideas may be differently embodied in various physical structures and arrangements within the scope of the appended claims, so that the invention is not 25 limited to the specific illustrated adaptation which will now be particularly described.

In the accompanying drawings:

Figure 1 is a sectional side elevation of 30 a bottle capping machine embodying the invention, the section being taken on the plane indicated by the lines 1, 1 in Figs. 2, 4, 5, 6, 7 and 8.

Fig. 2 is a front elevation of the machine 35 looking from a point at the left of Fig. 1.

Fig. 3 is a fragmentary front elevation from the same view point as Fig. 2 and showing the orbitally revolving hopper and capping head in a position different from its 40 position in Fig. 2, with a portion of the cap conveyer cut away to display the orbit link and eccentrics.

Fig. 4 is a front elevation of the said orbit link and eccentrics.

Fig. 5 is an enlarged front elevation of 45 the cap-feeding mechanism at the lower end of the cap conveyer, the view being indicated at the lines 5, 5 of Figs. 10 and 11.

Fig. 6 is a partly sectional plan view of 50 the machine taken on the plane 6, 6 of Figs. 1, 2 and 7.

Fig. 7 is an enlarged fragmentary front elevation partly in section on the plane 7, 7 of Figs. 1, 6, 12 and 13.

Fig. 8 is an enlarged fragmentary plan 55 view indicated by the view planes 8, 8 of Figs. 1 and 12, the hopper bracket 90 being removed.

Fig. 9 is a fragmentary rear elevation showing the mechanism for rotating the selector disk of the cap hopper, the view being indicated by the view plane 9 of Fig. 1, and the plate 72 of Fig. 1 being removed from the rack-guiding gear-box 71.

Fig. 10 is an enlarged sectional side elevation of the orbital capping head taken on the plane 10, 10 of Figs. 2, 5, 7 and 8.

Fig. 11 is a fragmentary side elevation from the same view point as Fig. 10 and looking toward the right side of the cap- 70 feeding mechanism of Fig. 5.

Fig. 12 is a sectional enlarged fragmentary side elevation of the orbital capping head and its orbit link and eccentrics, on the section plane 12, 12 of Figs. 2, 4, 5, 7 and 8. 75

Fig. 13 is a sectional enlarged fragmentary side elevation of the bottle carriage and conveyer chain, on the section plane 13, 13 of Figs. 2, 6 and 7.

Fig. 14 is an enlarged sectional side elevation of the self-adjusting device of the cap-feeding mechanism, the view point being the same as that of Figs. 1 and 12, and the section being taken on the plane 14, 14 of Figs. 2 and 15. 80

Fig. 15 is a front elevation of the link-guiding block 48 of Figs. 1, 12 and 14, with the front plate 49 and link 53 removed.

The main frame casting 21 carries a bracket upon which is mounted the motor 22 which drives the vertical main shaft 25 through a spur gearing 23 and a worm gearing housed in the gear-box 24. Through bevel gearings 26, 27, 28, 29, 30 and 31 the vertical main shaft drives the three horizontal shafts 32, 33 and 34 arranged in a common vertical plane. The shafts 32 and 33 drive the orbital capping head, while the shaft 34 drives the reciprocating bottle carriage. 90

On the front ends of the shafts 32 and 33 are crank disks 35 and 36 whose cranks or eccentrics 37 and 38 are of equal throw and carry the vertical pitman or orbit link 39, upon which the capping head is mounted by dove-tail gibbs formed on the orbit link and embraced by the rearwardly extending lugs 91 cast on the spring barrels 88 of the cap- 100 105

ping head—see Fig. 8. The purpose of this vertically slideable connection between the orbit link and the capping head is to adjust the vertical position of the capping head to various elevations above the bottle carriage 115, in order to adapt the machine to bottles of various lengths, and the adjustment is effected by means of a vertical screw 41 whose thread turns in a lug 40 on the orbit link and whose upper end turns in a lug 45 on the capping head, the screw being turned by bevel gears 42 and 43 which connect it with the key 44 projecting frontward through the capping head and the middle of the cap conveyer 110. When the vertical position of the capping head has been thus adjusted, it is locked by a screw 92 threaded in one of the lugs 91 to bear on the gib of the orbit link.

20 The construction and operation of the double capping head here illustrated are familiar, excepting its orbital movement in a vertical plane, and the following novel features:

25 The selector disk 75 which feeds the bottle caps from the hopper 76 to the cap conveyers 77, is oscillated by a geared rack 70 pivoted to a bracket 69 on the main frame and meshing with a pinion 73 which turns the selector shaft 74. A gear-box 71 pivoted on this shaft incloses the pinion and guides the rack, and is closed by a rear plate 72—Figs. 1 and 9.

30 The cap-feeding fingers 66 are mounted on shafts 65 having levers 67 held by springs 68 so as to maintain the fingers 66 normally in cap-retaining positions, and levers 64 on these shafts are engaged by the downward movement of the plunger 62 to swing the shafts and cap-feeding fingers to cap-releasing positions. A bracket casting secured on the front side of the spring barrels of the casting head forms bearings 57 for the rock-shaft 56, and also a guide 58 for the plunger 62 secured therein by a rear plate 59. Projecting from the right side of the plunger 62 is a pin 61 engaged by a radial slot in the rock-arm 60 secured on the rock-shaft 56, so that when this rock-shaft 45 is turned by the lever 55 on its left end the plunger will be lowered or raised to its lower or upper limit fixed respectively by the lugs 130 and 63 secured on the plunger in positions to engage the upper and lower ends of the guide bracket 58. The actuating rock-arm 55 extends rearward from the rock-shaft 56 and is connected by a universal joint 54 with the lower end of the inclined self-adjusting link 53 which in turn 50 is connected by a sliding universal joint with the anchor bracket 46 on the main frame. This sliding universal joint shown particularly in Figs. 14 and 15 comprises a rocking head 47 pivoted to the anchor bracket 46 to swing in a vertical plane, and

55 a guide block 48 pivoted to the rocking head by a stud 50 so as to swing thereon in a plane at right angles to said vertical plane, said guide block forming a channel in which the self-adjusting link 53 may slide beneath the front plate 49 screwed to the guide block and having spring chambers 52 counter-bored from the inside to receive fiber buttons 51 which are forced against the front surface of the link by the compression springs in said chambers. As the capping head is orbitally revolved by the eccentrics 37 and 38, the link 53 imparts to the rock-arm 55 that amount of movement necessary to reciprocate the plunger 62 between its stops, and the friction of the fiber buttons 51 upon the link is sufficient to prevent its sliding in the guide block in this normal operation of the machine; but when the elevation of the capping head is altered by means of the adjusting key 44, the link is forcibly slid in the guide block to assume a corresponding readjustment.

60 In the spring barrels of the capping head, the ejecting spring 79 and the heavier cap-crimping spring 81 are employed in the usual manner, but the movement of the hollow plunger 80 into the spring barrel 88 is resisted also by a supplemental spring 84 contained in the hollow boss 86 formed on 65 either spring barrel. The supplemental spring surrounds the stem 85 of the supplemental plunger whose head 83 is guided in the bore of the said hollow boss and whose said stem is guided in a central bore in the 70 plug 87 screwed into the opening of the hollow boss. Thus the supplemental spring is compressed between the plug and the plunger head 83 so as to force this head inward and against a wear-plate 82 set in the hollow plunger 80 and provided with a recess into which the head fits and whose lower margin forms a slanting cam surface engaged by a corresponding bevel on the edge of the plunger head. Manifestly, during the 75 initial movement of the hollow plunger 80 into the spring barrel 88, the cam engagement of the wear-plate 82 and spring head 83 must move the supplemental plunger outward against the resistance of the supplemental spring 84 until the head 83 rides out of its co-acting recess in the wear-plate and finds its bearing on the vertical front surface of this plate, after which the further upward movement of the hollow plunger 80 will be resisted only by the friction of the spring head 83 and the opposition of the vertical compression spring 81. In normal operation the hollow plunger 80 does not rise in the spring barrel 88 far enough to 85 ride the supplemental spring head 83 out of the cam recess in the wear plate, but when an unusually high bottle or stiff cap is encountered the resulting abnormal travel of the plunger 80 into the spring barrel will 90

carry the cam surface in the wear-plate 82 beyond the co-acting bevel on the spring head 83 so as to reduce the total resistance to further movement and thus avoid breakage of the bottle.

The carriage driving shaft 34 is journaled in the carriage bracket 93 secured on the main frame, and carries a crank 113 upon which is mounted a roller 114 working in the vertical slot of a reciprocating yoke formed on the bottle carriage 115 so as to reciprocate the carriage in response to the rotation of the crank and roller. The bottle carriage rides on rollers 117 which roll on the tracks 131 secured to the carriage bracket, and the carriage is held in place by guide bars 119 set flush in grooves in the upper surfaces of the carriage and the bracket and secured to the bracket by screws. Thus the carriage and bracket and guides are rendered all flush with one another, and flush extension plates 120 and 121 are secured to the carriage and project respectively over the receiving shelf 129 and under the bottle-feeding turret 127 so that the bottles may be slid without interference from the turret and over the carriage and on to the receiving shelf. The radius of the carriage-driving crank 113 is the same as the radii of the equal throw cranks 37 and 38 which carry the orbitally revolving capping head, and all three cranks are set in synchronism, so that the reciprocating movement of the bottle carriage will at all times correspond exactly with the horizontal component of movement of the capping head, whereby the relative movement between the bottle carriage and capping head is reduced to the simple vertical component of the capping head movement. In other words, there is no relative horizontal movement between the bottle carriage and the capping head; and suitable resilient pads 118 are set flush in the upper surface of the carriage concentrically with the capping heads, to receive the bottles while under the pressure of the capping operation.

The front end of the carriage driving crank 113 is mounted on a small shaft section 95 which projects through an outboard bearing 94 secured to the carriage bracket and carries a spiral gear 96 driving a horizontal spiral gear 97 which in turn drives the vertical shaft 99 journaled in a bearing 98 formed on the carriage bracket. At its upper end the vertical shaft 99 drives the horizontal sprocket 100 which in turn drives the bottle-conveying chain consisting of alternate finger links 102 and connecting links 101, and running over a right-hand sprocket 132 fixed on the upper end of a vertical shaft 103 which turns in a bearing 133 formed on the carriage bracket and at its lower end carries a horizontal sprocket which drives the chain 124 to rotate the sprocket 125 fixed

on the lower end of the vertical turret shaft 126 turning in a bearing formed on the turret bracket 134 secured to the carriage bracket 93.

At its upper end the turret shaft 126 drives the bottle turret 127 resting on the said turret bracket and surmounted by a central curb 128 also mounted on the turret shaft and turning with the turret. The turret is surrounded by an outer arcuate curb 123 suitably secured to the turret bracket, and bottles placed on the front side of the turret are by its rotation carried rearward between its central curb 128 and outer curb 123, and thence leftward toward the bottle carriage. The bottles are thus crowded against a gate 109 which arrests their further movement while the turret slides under them, until the gate is swung leftward by a rocking movement of the shaft 135 which turns in the casting of the outer bottle curb 123 and whose upper end carries the gate and whose lower end carries an arm with a vertical pin 107 embraced by the slotted end of the lever 105 pivoted to the turret bracket at 106 and actuated by a cam 104 turning with the aforesaid vertical shaft 103, the cam being designed and timed to open and close the gate so that each bottle will be carried into the proper embrace of one of the finger links 102 of the conveyer chain. A suitable spring 108 keeps the lever 105 in engagement with the cam 104.

Each bottle thus engaged by the conveyer chain is carried by the chain on to the bottle carriage, and the speed and spacing of the finger links are such that the successive bottles will be carried in successive pairs on to the centers of the receiving pads 118 as the capping head comes down to seal the bottles. The finger links move leftward relative to the bottle carriage and slide the bottles leftward over the carriage until that instant when the leftward movement of the carriage is accelerated up to the velocity of the finger links, and it is at this instant that the bottles are centered on the receiving pads 118. After this critical instant the bottles are carried leftward ahead of the finger links by movement of the carriage 115 and capping head while the capping head comes down to apply the caps. After the caps are applied and the capping head has released the bottles, they are again overtaken by the finger links as the leftward movement of the carriage is decelerated, and thereafter the chain conveys the sealed bottles to the receiving shelf 129.

As aforesaid, the principles of the machine may be practised in different specific mechanisms within the spirit of the invention and the scope of the following claims:

1. A bottle capping machine comprising means including a bottle carriage for imparting to the bottles a continuous recti-

linear bottle progressing movement transversely of the length of the bottles, a capping head, and means for moving the capping head to and from the bottle carriage to apply the bottle caps and for concurrently moving the capping head transversely with the bottles during the capping operation.

2. A bottle capping machine comprising a capping head and a bottle carriage and means for moving the capping head vertically to and from the bottle carriage to apply the bottle caps and for simultaneously moving the capping head and carriage together rectilinearly in a given vertical plane in bottle progressing direction and at the same velocity during the cap-applying action of the capping head.

3. A bottle capping machine comprising a capping head and a bottle carriage beneath it and means for moving the capping head orbitally in a vertical-plane orbit and for rectilinearly reciprocating the carriage horizontally in said vertical plane of the capping head orbit and at a velocity equal to the horizontal component of the capping head movement during its cap-applying engagement with the bottle.

4. A bottle capping machine comprising two vertical-plane eccentrics, means for rotating them synchronously in angular phase correspondence, a capping head mounted on said eccentrics to be orbitally revolved thereby in a vertical plane, a bottle carriage below the capping head, and means for moving the carriage horizontally in bottle progressing direction at the horizontal velocity of the capping head during its cap-applying action.

5. A bottle capping machine comprising two vertical-plane eccentrics of equal throw, means for rotating them synchronously in angular phase correspondence, a capping head mounted on said eccentrics to be orbitally revolved thereby in a vertical plane, a bottle carriage below the capping head provided with a slot, a third eccentric working in the slot and having a throw equal to the throw of said vertical-plane eccentrics, and means for driving said third eccentric in synchronism and phase correspondence with said vertical-plane eccentrics.

6. A bottle capping machine comprising three vertical-plane eccentrics of the same radii and located at three elevations, means for rotating them synchronously in angular phase correspondence, a capping head mounted on the upper two of said eccentrics to be orbitally revolved thereby in a vertical plane, and a bottle carriage below the capping head and provided with a vertical slot embracing the lowest of said eccentrics.

7. A bottle capping machine comprising an orbit device and means for revolving it in a vertical plane orbit, a capping head

mounted on the orbit device and vertically adjustable thereon, a bottle carriage below the capping head, and means for rectilinearly moving the bottle carriage in a vertical plane horizontally with the capping head during the lower part of the orbital revolution of the capping head.

8. A bottle capping machine comprising two vertical-plane eccentrics and means for rotating them and a link carried by the eccentrics in a circular orbit, a capping head adjustably mounted thereon and means for adjusting its vertical position on the link, a bottle carriage below the capping head, and means for reciprocating the bottle carriage in correspondence with the horizontal component of the orbital link movement.

9. The invention claimed in claim 3 in combination with cap storing and feeding means carried with the capping head in its orbital movement and including a cap-feeding rotor, a gear connected with the rotor, and a rack meshing with the gear and pivoted at a fixed point whereby to rotate the rotor in response to its orbital movement of translation with the capping head.

10. The invention claimed in claim 4 in combination with cap storing and feeding means carried with the capping head in its orbital movement and including a cap-feeding rotor, a gear connected with the rotor, and a rack meshing with the gear and pivoted at a fixed point whereby to rotate the rotor in response to its orbital movement of translation with the capping head.

11. The invention claimed in claim 3 in combination with cap-feeding means carried with the capping head in its orbital movement, and a link forming an actuating connection between said cap-feeding means and a fixed point and pivoted so as to accommodate the orbital movement of the capping head.

12. The invention claimed in claim 4 in combination with cap-feeding means carried with the capping head in its orbital movement, and a link forming an actuating connection between said cap-feeding means and a fixed point and pivoted so as to accommodate the orbital movement of the capping head.

13. The invention claimed in claim 7 in combination with cap-feeding means carried with the capping head in its orbital movement, an inclined universally pivoted link forming an actuating connection between said cap-feeding means and a fixed point for accommodating the orbital movement of the capping head, and friction sliding means in said connection to accommodate said vertical adjustment of the capping head.

14. The invention claimed in claim 8 in combination with cap-feeding means carried with the capping head in its orbital move-

- ment, an inclined universally pivoted link forming an actuating connection between said cap-feeding means and a fixed point for accommodating the orbital movement of 5 the capping head, and friction sliding means in said connection to accommodate said vertical adjustment of the capping head.
15. A bottle capping machine comprising two vertical-plane eccentrics, means for rotating them synchronously in angular phase correspondence, a capping head mounted on said eccentrics to be orbitally revolved thereby in a vertical plane, a bottle carriage below the capping head, and means for moving 10 the carriage horizontally in bottle progressing direction at the horizontal velocity of the capping head during its cap-applying
- 15

action, said means including a third eccentric and a slotted guide therefor.

16. A bottle capping machine comprising 20 three vertical-plane eccentrics of the same radii and two of which are located at a greater elevation than the third, means for rotating all three eccentrics synchronously in angular phase correspondence, a capping 25 head mounted on the upper two of said eccentrics to be orbitally revolved thereby in a vertical plane, and a bottle carriage below the capping head and provided with a vertical slot embracing the lowermost of said 30 eccentrics.

In testimony whereof, I have affixed my signature to this specification.

CARL WALKER KENDALL.
